UNITED STATES PATENT OFFICE.

EDWIN M. CORYELL, OF NEW YORK, N. Y., ASSIGNOR TO JULIA E. CAMERON,
OF SAME PLACE.

DESIGN FOR AN AIR-CHAMBER FOR PUMPS.

SPECIFICATION forming part of Design No. 31,080, dated June 27, 1899.

Application filed June 1, 1899. Serial No. 719,039. Term of patent 14 years.

To all whom it may concern:

Be it known that I, EDWIN M. CORYELL, a citizen of the United States, residing in the city and State of New York, have invented 5 and produced a new and useful Design for Air-Chambers for Pumps, which is fully set forth in the following specification.

The drawing showing my invention is an elevation of the air-chamber used in connection with a pump.

As shown in the drawing, the leading or material feature of my design consists in the substantially acorn-shaped configuration of the air-chamber. More particularly the latter consists of the lower portion 1, substantially hemispherical; the middle portion 2, substantially cylindrical and of less diameter than portion 1, the upper portion 3, also substantially cylindrical, but of still less di-

ameter than portion 2, the shoulder 4, connecting portions 1 and 2, and the curved portion 5, connecting portions 2 and 3 and substantially the frustum of a sphere. In addition the drawing shows the elbow 6, joined to the bottom of portion 1, and the flange-plate 7, secured to the top of portion 3.

Having thus described my invention, what I claim as new, and desire to secure by Letters Patent, is—

The design for an air-chamber for pumps, as herein shown and described.

In testimony whereof I have signed this specification in the presence of two subscribing witnesses.

EDWIN M. CORYELL.
